[57] CLAIM

The ornamental design for a chair, as shown and described.

DESCRIPTION

FIG. 1 is a perspective view of the chair from the front-left side;

FIG. 2 is a front plan view of the chair;

FIG. 3 is a top view of the chair;

FIG. 4 is a right side view of the chair;

FIG. 5 is a bottom view of the chair; and,

FIG. 6 is a back view of the chair.

The broken lines shown in FIG. 1 are for environmental purposes only and form no part of the claimed design.
